UNITED STATES PATENT OFFICE.

JOHN CLATWORTHY, OF PLUMSTEAD, ENGLAND, ASSIGNOR TO D. GESTETNER,
LIMITED, OF LONDON, ENGLAND.

DUPLICATING WITH THE AID OF STENCILS.

No Drawing.

Application filed March 29, 1924. Serial No. 702,999.

To all whom it may concern:

Be it known that I, JOHN CLATWORTHY, a British subject, and residing at 109 Tuam Road, Plumstead, in the county of Kent, 5 England, have invented certain new and useful Improvements in and Relating to Duplicating with the Aid of Stencils, of which the following is a specification.

This invention relates to duplicating 10 drawings, manuscript and typewritten matter and the like with the aid of stencils cut by the employment of a style or in a typewriter.

As is well known, in producing such stencils combined stencil sheets comprising essentially a foraminous support, such as Yoshino paper, provided with what may be described as a stencil layer and a backing sheet formed of a somewhat rigid or hard 20 surfaced non-absorbent paper, which in some cases is provided over the greater portion of its surface with a coating of ordinary printing ink are employed.

When using a combined stencil sheet of 25 this kind, even when the stencil layer contains a white pigment, the lines or characters cut in the stencil layer do not show up at all clearly against the black or dark-coloured background.

30 The object of the present invention is to provide an improved combined stencil sheet which will enable the impressions formed in the stencil layer to be more legible.

The invention consists broadly in a combined stencil sheet having a hard-surfaced backing sheet coated on that portion of its surface which is in contact with the sheet adapted to be stencilized, with a composition containing a colouring matter adapted 40 to be transferred to the stencil sheet where pressure is applied thereto by the means operating to cut the stencil layer.

The colouring matter will be one which contrasts with the colour of the stencil layer; 45 thus, it could be a white pigment if the stencil layer were dark in colour, while if the stencil layer is substantially white the colouring matter used would be dark in colour being, for instance, substantially black.

50 In this connection it may be remarked that the invention is mainly concerned with stencil sheets in which the stencil layer contains a white pigment and therefore in its more restricted scope it may be stated to consist in a combined stencil sheet comprising

50 a sheet of foraminous material provided with a stencil layer containing an opaque white pigment and a backing sheet therefor consisting of a sheet of hard-surfaced paper, coated on that portion of its surface which is in contact with the foraminous material provided with the stencil layer with a composition containing a colouring matter adapted to be transferred to the stencil sheet where pressure is applied thereto by the 55 means operating to cut the stencil layer.

The composition containing a colouring matter may be of any convenient character. It should, however, contain nothing which will operate to modify materially the properties of the stencil layer, and should, moreover, be of a character to resist or minimize the tendency of the backing sheet to absorb the tempering agent or other constituents of the composition constituting the stencil 70 layer. A transferring ink, such as an ink having a petroleum jelly base or a wax and colour composition of the kind used in forming the so-called carbon paper may, for instance, be employed.

80 The following particulars are given by way of example to illustrate a suitable method of carrying the invention into effect:—

A sheet of stiff hard-surfaced paper is 85 coated over a considerable portion of its surface with a layer of an ink formed by grinding lamp-black and, if desired, a small proportion of Prussian blue, in mineral jelly.

To a portion of the sheet thus treated, adjacent to one edge thereof, a sheet of Yoshino 90 paper provided with a stencil layer is connected by means of an adhesive, a cover sheet being optionally secured in position over the stencil layer by means of an adhesive applied over that portion of the sheet 95 of Yoshino paper which is connected with the backing sheet.

As will be understood, the combined stencil sheet in accordance with the invention presents considerable advantages over the 100 known combinations in connection with which it has been proposed to insert between the backing sheet and the stencil sheet a sheet of "carbon" paper, in that firstly the composition with which the sheet is coated 105 resists or inhibits the tendency of the backing sheets to absorb the tempering agent from the composition of which the stencil layer is formed and thus operates to keep the stencil in condition for use and, second- 110

ly, the time and trouble involved in introducing a sheet of carbon paper between the stencil sheet and backing sheet is saved.

Having now described my invention, what I claim as new and desire to secure by Letters Patent is:—

1. A combined stencil sheet for use in duplicating, comprising a sheet adapted to be stencilized by pressure and a hard-surfaced 10 backing sheet coated on that portion of its surface which is in contact with the sheet adapted to be stencilized, with a composition containing a colouring matter adapted to be transferred to the sheet where pressure 15 is applied thereto by the means operating to cut the stencil layer.
2. A combined stencil sheet for use in duplication, comprising a sheet of foraminous material provided with a coating of a material 20 adapted to be stencilized by pressure, and a sheet of hard-surfaced paper coated on that portion of its surface which is in contact with the sheet of foraminous material with a composition containing a colouring 25 matter adapted to be transferred to the stencil sheet where pressure is applied thereto by the means operating to cut the stencil layer.
3. A combined stencil sheet for use in duplicating, comprising a sheet of foraminous material provided with a coating adapted to be stencilized by pressure, a hard-surfaced 30 backing sheet connected thereto and on the surface of the backing sheet which is adjacent to the sheet of foraminous material a coating of a composition adapted to resist or inhibit the tendency of the material of the 35 backing sheet to change the properties of

the coating of the sheet of foraminous material and containing a colouring matter 40 adapted to be transferred to the coated sheet of foraminous material where pressure is applied thereto by the means operating to cut the stencil.

4. A combined stencil sheet for use in duplicating, comprising a sheet of material including a tempering agent adapted to be stencilized by pressure, a hard-surfaced 45 backing sheet detachably connected therewith and a coating of a composition on the 50 face of the backing sheet contacting with the sheet adapted to be stencilized by pressure, said composition carrying a colouring matter and being adapted to be transferred to the last-mentioned sheet in the operation of 55 stencilizing and including materials adapted to prevent the absorption of the tempering agent by the backing sheet.

5. A combined stencil sheet for use in duplicating, comprising a sheet of material including a tempering agent adapted to be stencilized by pressure, a hard-surfaced 60 backing sheet detachably connected therewith and a coating of a composition on the 65 face of the backing sheet contacting with the sheet adapted to be stencilized by pressure, said composition carrying a colouring matter and being adapted to be transferred to the last-mentioned sheet in the operation of 70 stencilizing, including materials adapted to prevent the absorption of the tempering agent by the backing sheet and inert to the stencil composition.

In testimony whereof I have signed my name to this specification.

JOHN CLATWORTHY.
